DESIGN FOR A SERVING OVEN

Ralph N. Kircher, West Bend, Wis., assignor to West Bend Aluminum Company, West Bend,
Wis., a corporation of Wisconsin

Application August 4, 1938, Serial No. 79,094

Term of patent 14 years

To all whom it may concern:

Be it known that I, Ralph N. Kircher, a citizen of the United States, residing at West Bend, in the county of Washington and State of Wisconsin, have invented a new, original, and ornamental Design for a Serving Oven, of which the following is a specification, reference being had to the accompanying drawing, forming a part thereof, and in which:

I claim:

The ornamental design for a serving oven, as shown.

RALPH N. KIRCHER.
